UNITED STATES PATENT OFFICE.

LUMAN F. JOHNSON, OF CLEVELAND, OHIO.

FURNACE-DOOR.

SPECIFICATION forming part of Letters Patent No. 297,808, dated April 29, 1884.

Application filed December 3, 1883. (No model.)

To all whom it may concern:

Be it known that I, LUMAN F. JOHNSON, a citizen of the United States, residing in Cleveland, in the county of Cuyahoga and State of Ohio, have invented certain new and useful Improvements in Furnace-Doors, of which the following is a specification.

My invention relates to furnace-doors which are suspended by a chain or its equivalent so as to be closed or opened by being raised or lowered in the usual way and by the ordinary means in use for such purposes. Such doors are subjected to a great heat all the time they are in use, and many devices have been made and tried with the object of getting something that will stand the intense heat and hard work they are subjected to.

The object of my invention is to produce a door having the fire-brick only exposed to the heat, the construction being such that the metallic portion of the door by which the fire-brick are held in place is exposed to as little heat as possible, all of which will be fully and clearly hereinafter shown by reference to the accompanying drawings, in which—

Figure 1 is a front or outside view of the door. Fig. 2 is a top or end view of the same. Fig. 3 represents a bottom or lower edge view. Fig. 4 is an inside face view of the door; and Fig. 5 is a detached section through a portion of the door and angle-plate for holding the bricks in place.

The metallic portion *a* or frame for holding the fire-brick in place is provided with a holding-piece, *a'*, bolted to the same by bolts *a''*. It is provided with an eye, *a'''*, through which the bolt passes that connects it to the end of the chain by which the door is suspended and held in place; but as this part of the device is in common use and well known, a further description of it here is unnecessary. The holding-piece *a'* is formed so as to project over the top of the door and hold the bricks in place at that point. (See *a'* in Fig. 2.)

a'' represents the fire-bricks, of which there may be more or less than the number shown.

The frame *a* is provided with a dovetail-shaped opening or side pieces, *b* *b'*, and the sides of each brick are provided with a groove, *b''*, of corresponding shape, so that the bricks 50 can be made to slide in place.

The side pieces, *b* *b'*, (or opening,) may be made of any form adapted to hold the brick in place, the grooves in their sides being made to correspond.

c represents an angular holding-piece for securing and holding the bottom brick in place. The part *c* is bolted to the frame or plate *a* by a bolt, *c'*, and the portion *c''* projects downward into a recess in the brick, (see Fig. 5,) 60 thereby holding it firmly in place and securing all the bricks above it.

c' is a modified device for the same purposes. It is also an angle-plate, the portion *c'* being bolted to the door frame or plate *a* by bolts *c''*, 65 and the lower portion (which is formed at right angles to the part *c'*) projects so as to rest against the bottom edge of the door and brick, thereby holding the bricks in place. It is provided with air-holes *e*, which lead to holes *e'* 70 in the door-plate. These holes lead into an air-space, *f*. (See Fig. 2.)

The object of the holes *e* is to permit a current of air to pass into the air-space and up out of the top of the door, and thereby carry 75 off a portion of the heat, so as to keep the casting or door-plate and bricks cool. By this construction the face of the brick only is presented to the fire, and when a brick is burned or otherwise rendered useless it (or all of the 80 brick) may be easily taken out and new ones put in their place when required.

I claim as my invention—

A furnace-door consisting of the casting or plate *a*, having the side pieces, *b* *b'*, and the air-space *f* and holes *e*', in combination with the bricks *a''* and holding-pieces *a'* and *c*, substantially as and for the purposes described.

LUMAN F. JOHNSON.
